DISCHARGE HEAD FOR FLUID CONTAINERS

Scott E. Allen, Glen Ridge, N. J., assignor to
C-O-Two Fire Equipment Company, Newark,
N. J., a corporation of Delaware

Application October 9, 1934, Serial No. 747,561

5 Claims. (Cl. 169—11)

The present invention relates to discharge heads of the type adapted to release a fluid from a container in which the fluid is held under compression.

5 An object of the invention is to provide a novel discharge head which is operable either by manual means or by fluid pressure or conjointly by both.

The invention is more particularly adapted for 10 discharging containers holding carbon dioxide liquefied under pressure. Such liquids are usually contained in steel cylinders having discharge openings closed by sealing disks which have to be punctured or cut open to release the fluid.

15 In certain discharge heads applied to carbon dioxide cylinders, a rotary cutter is provided which is operated by turning a hand wheel to cut the sealing disk. Sometimes it happens that the manual operation is not fully completed and

20 the opening in the cylinder disk is not sufficient to provide a free discharge of the fluid. It is, therefore, an object of the present invention to provide a structure in which the rupturing or cutting of the disk may be initiated by manual operation, but as soon as any fluid is released it

25 will operate to complete the cutting or puncturing of the disk, thereby insuring a complete opening. In other words, the operator is under no responsibility to effect complete turning of the hand wheel since as soon as any of the fluid is released, of which he will be apprised by the sound of the escaping fluid, he will be sure that the discharge head will complete the operation of making a full opening in the sealing disk.

30 A further object of the invention is to provide a discharge head of the character described above in which the entire operation may be performed by fluid pressure from an outside source without any interference due to the manual operating

35 means.

Other objects and advantages of the invention will appear in the following description of a preferred embodiment and thereafter the novelty and scope of the invention will be pointed out

40 in the claims.

The accompanying drawing is a view in vertical section through a discharge head embodying my invention.

In the drawing a cylinder 10 is fragmentally 45 indicated, this cylinder being adapted to contain a highly compressed fluid, such as carbon dioxide, which is to be discharged under control of my improved discharge head. The discharge head comprises three principal casing members 50 as follows: A body member 11 which is threaded

into the neck of the container 10; a cylinder member 12 which is secured to the body member by a coupling nut 13; and a cap member 14 which is screwed upon the outer end of the cylinder member 12. The body member is formed with a central bore 15 which is internally threaded near its lower end, as indicated at 16, to receive the usual siphon tube (not shown) which depends from the discharge head to a point near the bottom of the cylinder. Above the threaded part 16 there is a lateral port 17 fitted with a check valve 18 through which the cylinder 10 may be filled. Another lateral port 19 is provided with a safety disk 20 normally sealing the port but adapted to yield to a predetermined abnormal pressure, such as might arise from certain temperature conditions.

The upper end of the bore 15 is enlarged, as at 22, and is threaded to receive a screw plug 23. This plug is formed with a central bore 20 which, however, is closed by a sealing disk 24 attached to the bottom of the plug. When the plug is screwed home it seats against an annular step 25 formed at the bottom of the enlargement 22.

The casing member 12 is formed with a cylindrical working chamber 27 having a reduced lower extension 28. The latter communicates at its lower end with the enlargement 22 of bore 15. A piston 29 has a working fit in the chamber 27 and a tubular extension 30 of this piston fits into the extension 28. A piston ring 31 carried by the extension 30 insures a gas-tight fit between this extension and the bore 28.

A tubular cutter 32 is secured within the bore 35 of the extension 30 and projects into the bore of the plug 23. This tubular cutter is adapted to be thrust through the plug into cutting engagement with the cylinder disk 24 so as to release the fluid from the cylinder 10. The fluid thus 40 released may be passed through the hollow cutter and thence through ducts 34 formed in the piston to the chamber 27 above the piston. This fluid will press the piston downward against the action of a coil spring 35. A vent 36 permits escape of air from the bottom of the cylinder as the piston is forced downward.

The piston 29 is provided at its upper end with a stem 36 having an angular socket 37 therein. A correspondingly angled extension 38 of a vertical stem 39 has a sliding fit in the socket 37. The stem passes up through a threaded bore 40 in the cap member 14 and has a threaded portion 41 which engages the threads of the bore 40. A suitable stuffing box 42 serves to seal the joint be- 55

tween the stem 33 and the cap 14 ~~so as~~ to prevent escape of fluid. The stem 35 is provided at its upper end with a hand wheel 43. In the side of the cap member 14 there is a threaded port 45 5 communicating with the cylinder 27 and in which a discharge line may be screwed to carry off the discharge from the container 10.

The operation of the discharge head will now be apparent. Since the piston 29 is vertically 10 slideable with respect to the shaft 39 it will be evident that the piston may be depressed by the introduction of pressure fluid through port 45 into the top of the cylinder chamber 27. Thus, the sealing disk 24 may be punctured by the cutter 15 32 through the agency of fluid pressure controlled from a remote point. When it is desired to operate the discharge head manually, the hand wheel 43 is turned and, by reason of the threaded engagement between the stem 39 and cap member 20 14, the extension 38 will be forced downwardly. The cutter will be simultaneously turned and forced downward to engage and score the sealing disk 24. When the disk has been scored to sufficient depth the pressure of the fluid in the container 10 will tear open a flap of the disk and the gas thus released will pass through the cutter and piston to the top of chamber 27. The gas will then exert pressure upon the top of the piston and cause the piston to be forced immediately 25 and directly downward to complete the cutting of the disk. The operator, as soon as he hears the rush of escaping fluid will know that he does not need to turn the hand wheel 43 further because the cutting will have been automatically completed by the escaping fluid itself. Thus, I have provided a discharge head in which full opening is always assured if there is any opening whatsoever in the sealing disk. By providing a cutter which is turned as it is manually forced downward, the cutting of the disk will be effected with little expenditure of energy because there will 30 be a shearing or a scoring action rather than a direct punching pressure.

While I have described a preferred embodiment of my invention, it will be understood that this is to be taken as illustrative and not limitative and that I reserve the right to make various changes in form, construction and arrangement of parts as may fall within the spirit and scope 35 of the following claims.

I claim:

1. A discharge head for a container holding fluid under pressure, said container having an opening normally closed by a sealing disk, said 45 head comprising a hollow body having a discharge port, a cutter mounted in the body, manually rotatable means for advancing the cutter with a rotary motion to penetrate the disk and release said fluid into the body, and means operable by fluid pressure for advancing the cutter to penetrate the disk without rotation unless the cutter is being simultaneously rotated by said 50 manual means.

2. A discharge head for a container holding

fluid under pressure, said container having an opening normally closed by a sealing disk, said head comprising a hollow body having a discharge port, a cutter mounted to rotate and to slide axially in the body, manually operable screw 5 means for advancing and rotating the cutter to penetrate the disk and release said fluid into the body, and means operable by fluid pressure either independently of the manual means or conjointly therewith to advance the cutter and penetrate 10 the disk.

3. A discharge head for a container holding fluid under pressure, said container having an opening normally closed by a sealing disk, said head comprising a hollow body having a discharge port, a cutter, a screw threaded in the body, a spring urging the cutter off the disk and against the screw, means compelling rotation of the cutter with the screw, means for turning the screw to rotate and depress the cutter so as to 15 rupture the disk, and means operable by fluid pressure for moving the cutter axially with respect to the screw and causing the cutter to puncture the disk.

4. A discharge head for a container holding 25 fluid under pressure, said container having an opening normally closed by a sealing disk, said head comprising a body formed with a cylinder chamber having a discharge port, a piston reciprocable in the chamber below the port, a tubular cutter fixed to the piston and depressible thereby 30 to rupture the disk and release said fluid, the piston being formed with a passage for conducting the fluid therethrough to the top of the piston, means barring the fluid from access to the 35 underside of the piston, a vertical stem detached from the piston and projecting from the body, said stem being threaded in the body and arranged to bear downwardly against the piston, means for turning the stem to depress the piston 40 and rupture the disk, and coacting means on the stem and piston for causing rotation of the cutter as it is depressed by rotation of the stem.

5. A discharge head for a container holding 45 fluid under pressure, said container having an opening normally closed by a sealing disk, said head comprising a body formed with a cylinder chamber having a discharge port, a piston reciprocable in the chamber below the port, a tubular cutter depressible by the piston to rupture the 50 disk and release said fluid, the piston being formed with a passage for conducting the fluid therethrough to the top of the piston, means barring the fluid from access to the underside of the piston, a stem having an operating handle outside of the body and threaded through the body 55 into the chamber, the piston being formed with a socket of angular section, the stem having an extension of corresponding section fitting into but vertically slideable in the socket, and spring 60 means normally urging the piston against the stem.

SCOTT E. ALLEN.
